TRENT PROCESS CORPORATION, OF WASHINGTON, DISTRICT OF COLUMBIA, A
CORPORATION OF DELAWARE.

GRINDING MACHINE.

1,406,109.

Specification of Letters Patent. Patented Feb. 7, 1922.

Application filed September 3, 1920. Serial No. 407,867.

To all whom it may concern:

Be it known that I, WALTER E. TRENT, a citizen of the United States of America, residing at Washington, in the District of Columbia, have invented certain new and useful Improvements in Grinding Machines, of which the following is a specification.

The invention relates to improvements in grinding machines.

10 It is an object of the invention to provide an inexpensive balanced grinding machine, wherein the parts are associated and formed, so as to produce a maximum efficiency, while employing a minimum amount of power.

15 It is a further object of the invention to provide a rotary balanced grinding machine of a positive multiple stage construction, in which the material to be reduced, first passes from the source of supply in one direction through a pulverizing tube to be partially ground therein, and then passed through a second tube in an opposite direction prior to the discharge of the comminuted material.

20 With the foregoing conception in mind, the invention preferably comprises a multiple stage grinding machine having a central grinding tube that receives and partially reduces materials fed thereto, which materials are then substantially equally distributed to a series of pulverizing tubes disposed circularly around the central tube to balance the machine, and through which tubes the material must pass before its discharge to undergo a fine reduction therein.

25 It is a still further object of the invention to provide a multiple stage grinding machine having a central tube provided with grinding rods or balls of sizes larger than the sizes of the rods or balls disposed within the circularly disposed tubes surrounding the central tube so as to most effectively produce the stage of reduction that is to take place in the smaller tubes.

30 The invention also has among its objects the provision of a balanced grinding machine in which the component parts of the machine are entirely independent, thereby making the material positively subject to treatment for a specified travel or time of treatment before passing from one stage to a following stage. Further, in case of breakage, or wear, any component part may be removed, and replaced, without the necessity of changing other portions thereof.

The invention further contemplates the provision of a grinding machine, capable of either wet or dry grinding. When used for wet grinding, water is introduced to the central grinding tube with the material, and then distributed to the circularly disposed tubes with the partially pulverized material. If the material is to be ground dry, the same is fed into the central tube; and an air blast of sufficient volume and velocity is introduced to pick up and carry fine materials in suspension that have undergone sufficient pulverization, while the coarser materials are being acted upon by the grinding rollers, and when reduced to the proper degree of fineness, are carried by the air blast to a point of discharge.

From a more specific view, the invention consists of a balanced multiple stage grinding machine, having a common central grinding tube, provided with relatively large grinding rods, balls, or pebbles, and in communication with a plurality of circularly arranged auxiliary tubes, supported upon the central tube, and carried in unison therewith. The material introduced to the central tube is compelled to pass therethrough to undergo pulverization, after which the same is equally distributed to the various circularly disposed tubes to be further reduced, and caused to travel through such tubes to a point of discharge. It will be observed that the material introduced to the central grinding tube must pass through one tube and then to and through a second tube in a circuitous path, so that sufficient time and travel during grinding is provided, yet at the same time, to enable the machine to be constructed with but a relatively short length.

35 In the accompanying drawings I have disclosed several embodiments of the invention, but I wish it to be understood that this disclosure is merely made for the purpose of illustration, and the construction herein illustrated and described may be changed within the scope of the claims without departing from the spirit of the invention.

40 In the drawings, Figure 1 represents a top plan view of my apparatus.

Figure 2 is a side elevation with parts in section.

Figure 3 is an end view.

Figure 4 is a sectional view through the

apparatus showing the interior of the grinding tube; and

Figure 3 is a slightly modified form of the invention.

5 Referring now more particularly to the drawings, wherein like reference characters indicate corresponding parts, the numeral 1 designates a suitable base having arranged thereon the vertical standards 2, which constitute the supports for the bearings 3, and 4, of the machine.

10 The grinding machine consists of a central grinding tube 5, supported in the bearings 3 and 4, having annular collars 6, disposed within the recesses in the bearings 3 and 4, for the purpose of preventing the lateral movement of the central tube during its rotation. This tube, at its forward end, is provided with a feed chute 7, of a curved 15 formation, entering the central portion 8 of an end plate 9 of the central tube 5, and positioned so as to pass through a trough 10, supported upon the base 1 of the machine during the rotation of the central tube. The 20 feed 7 is additionally supported by a bracket 11, and the length thereof may vary depending upon the quantity of material that it is desirable to feed to the central tube from the feed trough 10, during a single rotation of 25 the tube.

30 The central tube 5 is of a relatively short length, having at its opposite end a gear wheel 12 keyed thereto, the said gear being located adjacent the end plate 14 of the central 35 tube, and meshing with a pinion 15 mounted upon a shaft 16 driven by a pulley 17, over which a belt passes leading from any suitable source of power. The shaft 16 is journaled in bearings 17 and 18, mounted 40 upon the frame, the said bearings being of a conventional structure. The interior of the central tube 5, is shown as being provided with a multitude of grinding rods 19, the same extending substantially throughout the 45 length of the tube to a point adjacent the screen 20. These rods, as disclosed in the cross sectional view, are of considerable diameter, and serve to reduce partially the relatively large comminuted material introduced 50 to the central tube 5 by the feed 7 during the passage of this material through the tube. The end plates of the tube are united thereto by bolts and nuts, so that said plates may be freely removed, for the purpose 55 of gaining access to the interior of the tube. In the prior art, difficulty has been experienced in providing a grinding machine having a sufficient grinding area effectively to reduce material to an exceedingly 60 fine state of division without making the grinding tube of great length, resulting in the mill being subjected to tremendous weight between its widely separated bearings. To obviate this difficulty, and yet at 65 the same time secure a maximum grinding

area, I have disposed around the central grinding tube 5, a plurality of auxiliary grinding tubes 20, 21, 22, 23, 24 and 25, six tubes being shown in the present illustration for the purpose of completely surrounding 70 the central tube 5, but it will be manifest that any number of tubes may be employed, this being largely dependent upon the size of the circular tube, and the working conditions for which the mill is to be utilized. It 75

will be appreciated that by arranging the circular tubes around the common central tube in the manner disclosed, the machine is balanced, and only a minimum amount of power is necessary to rotate the grinding 80 machine. The exterior tubes 20, 21, 22, 23, 24 and 25, are maintained in their proper relation upon the central tube 5 by the rods 26, and turn-buckles 27 connecting sections of said rod. The turn-buckles engage plates 28 85 to prevent injury to the tubes when the rods are tightly fastened thereto so as to cause the outer row of tubes at all times to rotate with the central tube, and permit no independent movement of said tubes relatively 90 to one another. Each circular tube is provided with suitable grinding rods 29, which are of sizes considerably less than the sizes of the rods 19 in the tube 5, inasmuch as the material delivered to the outer circularly arranged tubes is partly reduced, and the grinding area of these tubes is governed so as to accord with the stage of reduction that is to take place in the outer tubes. While I have shown grinding rods as a grinding medium, it will be appreciated that balls, pebbles, or the like, may be used with favorable results, the sizes being governed by the same principle as where rods are employed. 95

100 Leading from the central tube 5, and communicating with each outer tube 20, 21, 22, 23, 24, and 25, is a feed conduit 30, six of these conduits being disclosed, as one is provided for each outer grinding tube. The conduits 30 communicate with the interior of 105 the central tube 5 at one end receiving material that is passed through said tube, which material is transferred or delivered to the outer grinding tubes to undergo a further reduction therein, during the passage of such 110 material through said tubes to its point of discharge. The material introduced to the central tube is usually equally distributed to all of the outer tubes, each tube receiving its proper charge at one stage of its rotation, which charge passes through the tube, and is finally discharged in a manner which will be hereinafter described. The material fed to the central tube 5, after being reduced therein, enters the outer row of tubes, 115 the partially ground material passing to the tubes disposed beneath the center of the main tube 5 through the conduits 30, and in the disclosure shown in Figure 2, the tubes 21, 22 and 23, are receiving a supply of par- 120

tially ground material through their feed pipes 30, the continued rotation of the material causing the succeeding tubes 24, 25 and 20, to receive their charge when they reach the proper position, while the filled tubes are rotating to effect a grinding of the material introduced thereto. After the material has passed through the outer tubes, and has been reduced therein, the same is discharged from each tube by the curved discharge pipes 32. It will be seen that no material can be discharged from a tube when the discharge pipes are in an upwardly disposed position, but when the mill rotates the tubes are successively brought to the position disclosed in the lower portion of Figure 2, wherein the discharge pipes 32 are directed downwardly into the trough 33, and the finely ground material that has worked through the outer tubes is permitted to discharge successively into this trough. As has been stated, the material is successively discharged from the various outer tubes, and the operation of the machine is continuous, inasmuch as the material is being always introduced to the central tube, undergoing a preliminary treatment therein, and then substantially equally distributed and caused to pass through the outer tubes 20 to 25 inclusive, the path of the material being a circuitous one, so as to present a maximum grinding area.

In Figure 5 of the drawings I have disclosed another form of the invention, which is designed for dry grinding any substance. In this form, coal, or other material, is introduced to the hopper 34, and fed by the conveyor 35 to the central grinding chamber 36 mounted upon suitable standards 38 for a rotary movement. Air is injected by the pipe 39, for forcing the material through the central tube 36, the material passing therethrough and being partially ground by reason of the grinding rods disposed therein. When the material is ground to the desired fineness in the tube 36, the air current picks up the finer particles of the material, carries the same through the discharge pipes 40 in communication with one end of the tube 36, and also with the auxiliary tubes 41, six of these tubes being disclosed, which tubes are mounted in the same manner as disclosed in connection with Figure 1. The tubes 41 likewise have grinding rods, so that the partially ground material is further reduced in said tubes during the rotation thereof, and after passing through the tubes, discharges in the air current through the pipes 42, passing between the tubes to an opposite end of the central tube 36, which is separated from the remaining portion of the tube by the partition 43. The air carrying the fine material in suspension, then passes through the discharge pipe 44 into the dust collector 45, which is of any conventional type, the comminuted material settling in the lower portion of the receptacle, while the air passes on through the pipe 46 to the air compressor 47 to be again fed to the air feed pipe 39. This construction of the machine is rotated by means of a gear and pinion drive, as shown in Figure 1.

Having thus described the various parts of the machine, the operation may be briefly stated as follows:

Assuming that the apparatus shown in Figures 1 and 3, and intended for wet grinding is to be used, the material in a comminuted state and mixed with water, is introduced to the feed trough 10. The central grinding tube 5 is then rotated by means of the pulley 17 and gears 12, which impart rotation to the central tube, and the circular tubes carried thereby. The material must pass through the central tube, being acted upon by the tumbling rods 19, which serve to reduce the same to a relatively fine mesh, after which, said material is discharged through the discharge conduits 30 in substantially equal proportions to each of the circular tubes 20 to 25, inclusive; in a successive manner. That is, one tube receives its supply when it reaches a given position during its rotation, and a second tube then moves into position to receive its supply from the main tube 5. The material, after being introduced to the circular tubes 20 to 25, inclusive, is compelled to pass therethrough, being further pulverized by the reducing rods 19 tumbling therein, and after passage through said tubes, the material is discharged by the curved discharge pipes 32, into the trough 33. It will be noted that the material is compelled to travel in a circuitous path, and that the operation of the machine is a multiple stage one, permitting the material to be reduced to a minimum degree of fineness.

Should it be desirable to pass the material through more than two of the grinding tubes, it will be appreciated that the outer tubes 20 to 25, inclusive may be arranged in series, so that the material introduced to any one of these tubes through the central tube 5, may be caused to pass back and forth, through any desired number of tubes, in a circuitous path, prior to its discharge. This construction would only be necessary where the material is exceedingly hard and slow to grind and a product of excessive fineness desired.

If the material is to be ground in a dry state, then the apparatus shown in Figure 4 is employed, the material being fed into the hopper 34, and by the air, passing through the pipe 39, is forced into the central tube 36. The material undergoes partial reduction therein, the air current picking up particles of the material of the desired fineness, carrying them through the feed pipes 40 into

the auxiliary grinding tubes 41. Here the grinding of the material is completed, and the air current carries the pulverized material through the discharge pipes 42, the pipes 44, and into the dust collector 45, where the comminuted material is collected and the air exhausted, and passed together with any included particles to the air compressor 47 to be returned to the nozzle.

10 Having thus described the invention, what I claim is:

1. In a grinding machine, the combination with a common grinding tube having grinding elements therein, means for introducing material to said tube, a plurality of grinding auxiliary tubes adapted to move in unison therewith, means establishing a communication between one end of the common grinding tube and each of said auxiliary 15 grinding tubes to permit material that has passed through the common grinding tube to be introduced to one of said grinding tubes, and a separate discharge for each grinding tube disposed at a point opposite the feed inlet thereto and discharging the material into the atmosphere.

2. In a grinding machine, the combination with a common grinding tube having a feeding inlet, and provided with a grinding medium, means for mounting said tube for a rotary movement, a plurality of auxiliary grinding tubes carried by said common tube, and parallel therewith, means for firmly uniting said tubes to the central chamber to cause the same to rotate in unison therewith, grinding devices in the tubes, separate means establishing communication between the central tube at a point remote from its inlet and each of the auxiliary tubes for discharging partially ground material that has passed through said central tube to one of said auxiliary grinding tubes, and discharging means for said auxiliary grinding tubes for discharging material that has 40 passed therethrough.

3. In a grinding machine, the combination with a central grinding tube, a feeding inlet thereto, means for mounting said tube for a rotary movement, a plurality of parallel grinding tubes surrounding said central tube and adapted to move in unison therewith, grinding elements carried by said central tube and said grinding tubes, and separate means connecting said central tube with each of said surrounding grinding tubes for delivering material thereto to be passed through said parallel grinding tubes respectively in a circuitous path, and a discharge pipe leading from each of said surrounding tubes.

4. A grinding machine having a grinding tube mounted for a rotary movement having grinding elements therein, and a second tube of elongated formation having imperforate 65 side walls and provided with shiftable grind-

ing elements disposed in parallel relation therewith and driven with said first tube as a unit and in communication with one end of said first mentioned grinding tube, means for feeding material to said first mentioned grinding tube to pass therethrough, and to be then delivered to the last mentioned tube to travel lengthwise through said tube prior to its discharge, and a discharge for said last mentioned tube.

5. A grinding machine having a primary grinding tube, and an auxiliary tube having grinding devices therein in communication therewith and movable with said primary tube as a unit, disposed alongside the main 80 tube, and presenting side walls defining grinding areas which are imperforate and grinding devices in said auxiliary tube, means for rotating said tubes, means for feeding a material to the primary tube to 85 be passed therethrough, and to be then delivered to the auxiliary tube, said primary and auxiliary tubes being disposed side by side to cause the material introduced to the primary tube to pass through said primary 90 and auxiliary tubes lengthwise in a circuitous path prior to its discharge.

6. In a balanced grinding machine, the combination with a central grinding tube having grinding elements therein, of a plurality of auxiliary tubes arranged around said central tube in parallel relation therewith, said central and auxiliary grinding tubes having elongated grinding areas surrounded by imperforate walls and provided 100 with shiftable grinding devices, means for feeding material to the central tube, means for rotating said tube, and communications between one end of said central tube and the auxiliary tubes to cause the material introduced to the central tube to travel lengthwise through said central and auxiliary tubes in a circuitous path prior to its discharge.

7. In a grinding machine, the combination with a central grinding tube, of bearings therefor, auxiliary grinding tubes surrounding said central grinding tubes and in parallel relation therewith grinding devices disposed within said central and auxiliary tubes, means for uniting said auxiliary tubes to said central tube to cause all of said tubes to rotate in unison, a feed at one end of such central tube, discharge devices at the opposite end of said central tube communicating with the auxiliary tubes to deliver material from said central tube to the auxiliary tubes to pass lengthwise through said auxiliary tubes prior to its discharge.

8. In a grinding machine, the combination with a central grinding tube, of bearings therefor, auxiliary grinding tubes surrounding said central grinding tubes and in parallel relation therewith, grinding devices disposed within said central and auxiliary

- tubes, means for uniting said auxiliary tubes to said central tube to cause all of said tubes to rotate in unison, a feed opening at one end of such central tube, discharge devices at the opposite end of said central tube, communicating with the auxiliary tubes to deliver material from said central tube to the auxiliary tubes to pass through said auxiliary tubes prior to its discharge, and means for feeding the central tube comprising a scoop carried thereby and movable in a trough adapted to receive a supply of material.
9. A balanced grinding machine comprising a rotatable central tube having a feed inlet, of auxiliary tubes having imperforate walls intermediate their ends disposed around said central tube, means for uniting said auxiliary tubes to said central tube in proper spaced relation to rotate therewith as a unit, the central and auxiliary tubes being provided with grinding devices for reducing material introduced thereto, said central tube communicating at one end with said auxiliary tubes for distributing the material partially ground in the central tube to the auxiliary tubes to effect a further reduction of the material during its passage through the auxiliary tubes prior to its discharge.
10. A balanced grinding machine comprising a rotatable central tube having a feed inlet, of auxiliary tubes disposed around said central tube, means for uniting said auxiliary tubes to said central tubes in proper spaced relation, the central and auxiliary tubes having imperforate walls intermediate their ends and being provided with grinding devices for reducing material introduced thereto, and said central tube communicating at one end with said auxiliary tubes for distributing the material partially ground in the central tube to the auxiliary tubes to effect a further reduction thereof prior to its discharge, the material being forced to travel in a circuitous path while undergoing pulverization.
11. A grinding machine provided with a rotatable grinding chamber having grinding devices and a support therefor, auxiliary grinding chambers disposed alongside said main chamber and adapted to rotate therewith as a unit, means establishing communication between said auxiliary and main chambers, the walls of the auxiliary and main chambers defining grinding areas being imperforate to cause material introduced to the main chamber to travel in a closed path through said chamber and then lengthwise through said auxiliary grinding chambers prior to its discharge, and discharging devices for said auxiliary chambers.
12. In a grinding machine, the combination with a central grinding chamber having a feed inlet, means for supporting said chamber for a rotary movement, a plurality of auxiliary grinding chambers disposed alongside said main chamber and adapted to rotate therewith as a unit, grinding elements carried by said central and auxiliary grinding chambers, independent sources of communication connecting said central chamber with each of said auxiliary grinding chambers for delivering material thereto to be passed through said chambers in a circuitous path, and a discharge from each of said auxiliary grinding chambers.
13. A grinding machine comprising a rotatable grinding chamber having grinding devices therein adapted to receive material, means for supporting said chamber for a rotary movement, a second chamber provided with grinding means adapted to rotate with said first mentioned chamber as a unit, said last mentioned chamber being positioned alongside the first mentioned chamber, and constructed whereby material progressively passes through said chambers in a circuitous path prior to its discharge, and discharging means for said last mentioned chamber.
14. A grinding machine having a main grinding chamber, provided with reducing devices adapted to receive material, means for supporting said chamber for a rotary movement, an auxiliary chamber having grinding elements adapted to rotate with said main chamber as a unit and in communication therewith, said auxiliary chamber extending alongside the main chamber, said chambers being constructed to present a closed path for material introduced thereto whereby said material progressively travels lengthwise through one chamber, and then the other, prior to its discharge, and discharging means for said auxiliary chamber.
15. A grinding machine having a grinding tube adapted to receive grinding devices, feeding means for said tube, means for supporting the tube for a rotary movement, an auxiliary chamber having grinding means rotating with said first mentioned chamber as a unit, and communicating therewith, said auxiliary chamber being positioned alongside the primary chamber, both of said chambers having imperforate walls presenting a closed path for material introduced thereto, whereby said material progressively travels lengthwise through one chamber and then through the other prior to its discharge.
16. A grinding machine having a rotatable grinding tube provided with grinding devices, an auxiliary tube lying alongside said main tube, rotating as a unit therewith, and a communication between said tubes, the walls of said tubes defining grinding areas being imperforate whereby said tubes present a closed path for material introduced thereto to cause said material to progressively travel through the length of the grinding area of the one tube and then through the other prior to its discharge.

17. A grinding machine having a primary grinding tube and a feed inlet thereto, grinding devices for said tube, means for supporting the tube for a rotary movement, a plurality of auxiliary tubes disposed alongside said main tube, and rotating therewith as a unit, communications between said main tube and said auxiliary tubes, grinding elements in said auxiliary tubes, said main and auxiliary tubes being constructed with imperforate walls defining grinding areas, whereby material introduced to the main tube is compelled to travel lengthwise through said tube, and then distributed to the auxiliary tubes for passage through said tubes prior to discharge.
18. A tube mill, comprising a central tube and surrounding parallel tubes united thereto so as to rotate as a unit, grinding elements in each of said tubes, feed tubes leading from
- one end of said central tube to each of said surrounding tubes at adjacent ends, and separate discharge tubes for said surrounding tubes leading therefrom adjacent the feed end of said central tube, substantially as described.
19. A tube mill, comprising a central tube, and surrounding tubes substantially parallel with the central tube united thereto and rotatable as a unit, grinding elements in each of said tubes, means for feeding material from the central tube to the surrounding tubes after the passage of the material through the central tube, and discharge means from each of said surrounding tubes leading therefrom opposite the inlet to said tubes, substantially as described.

In testimony whereof I affix my signature.

WALTER EDWIN TRENT.
